ELECTRICAL SWIVEL DISCONNECTOR

Martin D. Bergan, Westfield, N. J., assignor to
 The Thomas & Betts Co., Elizabeth, N. J., a
 corporation of New Jersey

Application March 21, 1945; Serial No. 583,937

2 Claims. (Cl. 173—363)

1

This invention relates to a new and useful swivel electrical disconnector, the present application being a continuation-in-part of my former application entitled Electrical coupling disconnector, and filed January 15, 1943, under Serial Number 472,436.

A primary purpose of the invention is to provide a connector having contact parts which swivel in relation to each other and which have a dual function, wherein a firm mechanical disengageable grip and a low resistance electrical connection are independently established between the movable or oscillating parts.

Accordingly, the two independent connecting means perform their separate functions in a manner which provides a new mode of operation, affording maximum holding tension or pull-out value between members of given size, and likewise maximum current transmitting value therebetween.

The accompanying drawings illustrate the invention, present an example of its structural form, and suggest other embodiments which come within the principle of the invention.

The example of construction shown herein includes a disengageable contact ball and resilient clasp in the form of a wire terminal which provide for a dual mechanical and electrical connection, the ball or spherical member affording a free swiveling action between the two metallic parts constituting the connector.

The description and drawings herein explain the principle of the invention and present the best mode now contemplated in applying such principle, so as to distinguish the invention from others; and there is particularly pointed out and claimed, in so far as is known by comparison with the art, the part, improvement or combination, which constitutes the invention or discovery.

Fig. 1 shows the electrical connector in disengaged position. The connector terminal clasp is shown just above the contact ball, and in readiness to engage it.

Fig. 2 shows the connector parts plugged together, the diverging dotted lines indicating the range of angular or swiveling movement of the connector clasp in relation to the contact ball. In this view, the position of the connector clasp is shown at right angles to that of Fig. 1.

Fig. 3 is a sectional view taken on the line 3—3; while Fig. 4 is a section developed along the line 4—4.

Fig. 5 is a diagrammatic view of the spring gripping arms, forming a portion of the connector

2

clasp or terminal before and after making disengageable connection with the ball contact.

Fig. 6 is similar in purpose to the previous view, but illustrates the position of the electrical contact legs, another portion of the connector clasp, before and after making disengageable connection with the ball contact.

Referring further to the drawings, a ball or spherical contact 10 has a shank 11 carrying a wrench or tool-receiving portion in the form of a nut 12 by which to screw a threaded shank or stud 13 into a panel P of an instrument board or other device or machine part with which the connector may be used. Any suitable instrument 15 wiring connection (not shown) may be electrically connected with the threaded stud 13. The panel P merely represents one commercial application, while the threaded stud 11, 13 represents one of the many different types of mounting 20 means, and also a wire conductor receiving means, for the disconnect contact ball or spherical portion 10 of the connector.

A connector clasp or terminal, including a head or base 14, may be approximate in size, spread, 25 or area to that of the diameter of the contact ball 10. A wire conductor receiving means, in the form of a sleeve 15, is carried on the back side of the head 14 forming the base portion of the connector clasp, the reference number 14 designating the clasp as a whole. An electrical wire W (usually a flexible cable strand) is inserted into the sleeve 15 and bonded thereto in any approved manner. Thus current is transmitted from the wire W to the connector clasp 14 which is adapted 30 for manual clasping connect and disconnect operation (and a swiveling action if desired) in relation to the contact ball 10.

A set or plurality of resilient mechanical gripings arms 16 are shown as being formed integrally with the perimeter of the clasping head 14 (as at right angles thereto) and extended from the front side thereof toward the contact ball 10. The several mechanical gripping arms 16 are equidistantly spaced on the head 14 of the clasping terminal. The edges of the arms 16 are seen in Fig. 2, whereas in Fig. 1 their outer surfaces are seen, due to the fact that the two views show the connector clasp from two positions, one at ninety degrees from the other.

Each resilient arm 16 has a ball-pocketing finger 18 formed on its outer free end which flexes with the arm. And each finger 18 is curvilinearly or angularly formed to bow outwardly with an internal shape to fit the surface of the ball contact 10. Thus the outward bows provide inwardly

dished surfaces on the fingers 18, facing the axis of the clasp 14, and adapted to engage the ball 10 for establishing a disconnectable gripping hold thereupon.

For simplicity in illustrating the principle of the invention, Fig. 2 suggests that two mechanical gripping arms 16 are employed. The number of arms in excess of two is a matter of design and choice. Figs. 3 and 4 are to be considered as sections developed along the lines indicated on Fig. 2, but are presented to show three spaced gripping fingered arms 16, 18 as one type of connector produced in accordance with this invention.

The inside diameter of the ball-pocketing fingers 18 is pre-formed slightly less than the diameter of the ball 10. In other words, the resilient arms 16 are set to hold the fingers 18 on a predetermined diameter which will grip and hold the ball with an appropriate or given force to resist separation of the clasp 14 from the ball 10. Accordingly, the resilient arms 16 and their ball-gripping fingers 18 may be produced for manual connect and disconnect operation with an approximate given force, and thus have a separating or disconnect pull-out value in pounds of force applied thereto which is suited to the particular use for which the connector may be produced.

The dotted line position (Fig. 5) of the ball-gripping fingers 18 illustrate the inwardly sprung pre-set position thereof before being plugged onto the ball 10. The resilient gripping arms 16 are cammed apart when manually forced onto the ball, and then snap closed, as shown in solid lines. Thus the arms expand in camming over the high point (maximum diameter) of the ball 10, and then contract as the fingers 18 come to rest. This arrangement establishes a mechanically swiveled connection between the ball 10 and clasp 14.

Electrical contact legs or springs 19 are also integrally formed on the front side and at the perimeter of the clasp head 14, being equidistantly spaced between the ball-gripping arms 16, and equal in number to said arms for more satisfactory operation. These electrical contacts 19 are concentric with the axis of the clasp 14, as indeed also is true of the ball-gripping spring means 16, 18. The two groups of resilient members (arms 16 and contacts 19) in effect constitute an electrical plug-on receptacle for the ball 10 where the latter is mounted in stationary position as shown in the drawings, although in other installations the arrangement may be reversed and the clasp 14 may be mounted stationary so that it acts as a plug-in receptacle for receiving the manually operated disconnect ball 10.

The group of contacts 19, two or more thereof for satisfactory results, may be formed straight and extend from the head of the clasp 14 alongside of and between the specially shaped arms 16, 18. Thus the simple straight formation of the contacts 19 is in contrast with the shape of the mechanical gripping fingered arms, the reason for which will be explained. In this connection, note Fig. 6 which is a diagrammatic view presented in aid of explaining the functional distinction between the two sets of spring members 16 and 19 adapted for swiveling disconnect engagement with the contact ball 10.

The straight spring contact legs 19 (observing Figs. 1 and 6) are pre-set on a diameter somewhat smaller than that of the ball 10, that is, the distance across the circle which defines the position of the outer free ends is smaller than the ball

when not engaging it. The dotted lines (Fig. 6) show the pre-set or inwardly sprung contacts 19 which converge toward their outer free ends before (Fig. 1) plugging the connector clasp 14 onto the ball 10. But when the clasp and ball are fully engaged, the several contacts 19 line up in parallel relation.

When the outer ends of the electrical contacts 19 first engage the surface of the ball 10, the spherical surface of the latter acts to cam open and spread said contacts; and as the clasp 14 is pushed further onto the ball, the contacts 19 slide onto the maximum diameter of the ball and remain there, doing so without drop in the maximum spring-loaded tension or pressure imparted to the contacts by the maximum diameter of the ball. In other words, the group of contact legs 19 (in contrast to the action of the fingered gripping arms 16, 18) expand to a maximum to embrace the ball 10, and thereafter never contract or yield.

The latter characteristic means that the very maximum pressure engagement, of which a given size contact 19 is capable, is applied and maintained against the ball 10, thereby providing maximum current transmission through a swivel joint of low current resistance. Accordingly, the electrical contact legs 19 are designed and provided only for current transmission while, on the other hand, the fingered gripping arms 16, 18 are utilized for establishing the mechanical connection between the two parts.

Since independent parts or portions are provided for distinct mechanical and electrical connecting functions, it follows that modifying the function of one does not impair the function of the other. Consequently, in manufacturing operations, the mechanical connecting means (fingered arms 16, 18) can be formed with such appropriate tension and pull-out value, to release from the ball 10 by a heavy pull or a light pull, as required for a particular electrical installation without interference from or limitation by the electrical contact legs 19. Indeed, the constant pressure contact legs 19 make the same low-resistance electrical connection through a swivel joint of low pull-out value as one of high pull-out value.

It is noted that the mechanical gripping arms 16 and the contact legs 19 are alternately arranged, or staggered, one between the other. Also the outer flexible ends of the group of resilient members 16 and 19 converge to define a circle somewhat smaller than the size of the head portion 14 of the clasp. And by way of further comparison, the circular area bounded by the outer tip ends of the concentrically disposed members 16 and 19 is smaller than the diameter of the ball 10.

The wire W and disconnector clasp 14 readily swivel or oscillate upon the ball 10, if need be, as indicated by the angular spread or divergence of the dotted lines (wire W) in Fig. 2. Thus the connector finds utility in installations where it is desirable to afford play and movement of a conductor cable W leading off from its service connection 10 to some other apparatus, especially where a quick disengageable electrical connection is required.

It is noteworthy that the dual-function clamping terminal 14 lends itself to adjustment by a mechanic on the job. If need arises, he may readily increase or decrease the tension of the clasp on the contact ball 10 by carefully using his pliers to slightly open or close the mechani-

cal gripping arms 16 without disturbing their resilient pre-set strength designed and engineered by the manufacturer into the electrical contacts 19. Thus the connector remains constant in respect to its electrical connection, whether or not swiveled to various positions, but may be increased or decreased in respect to its pull-out value.

Additional advantages and commercial applications of use are also found by adapting the contact ball portion 10 to supporting or mounting means, and wire connecting means, other than the simple stud type 11, 12 here shown merely for convenience in explaining the principles involved in connection with a connector which may comprise two simple parts. Indeed, the terminal contact ball 10, with any suitable form of wire connection, other than as indicated at 13, may be attached to a wire conductor for plug-in connection with the terminal clasp 14 and not require support in a panel P or other like stationary member.

This invention is presented to fill the need for a useful swivel electrical disconnector. Various modifications in construction, mode of operation, use and method, may and often do occur to others, especially so after they have benefited from the teachings of an invention. Accordingly, this disclosure is exemplary of the principles and equivalents without being limited to the present showing of the invention.

What is claimed is:

1. An electrical wire connector in the form of a clasping terminal, comprising a head portion, from which extend several resilient members disposed concentrically about a common axis, and the outer free ends of which define a circle smaller in area than the size of the head portion, certain of the resilient members being formed straight and adapted to expand and remain expanded to establish and maintain constant electrical contact pressure on a ball with which the clasping terminal is adapted to cooperate, and other resilient members being bowed outwardly to form inside pocketing surfaces adapted to expand and thereafter contract to clasp the ball and establish a secure mechanical grip thereon, the straight and the bowed resilient

members being disposed alternately one to the other around said common axis.

2. An electrical disconnector comprising cooperating members in the form of a contact ball 5 and connector clasp, with means for connecting an electrical conductor to each member; wherein the clasp includes a head portion, from which extend resilient contact legs disposed on a common axis, the outer ends of the legs being free to flex, said legs converging toward their free ends and defining a circle which is smaller than the diameter of the ball, the legs resiliently engaging the ball and being expanded and spring tensioned and restrained against contraction by said ball, the reaction of such tension providing an electrical contact of maximum pressure between the ball at its maximum diameter and the converging legs; and resilient gripping arms also extending from the head portion and disposed on said axis and also converging as well as defining a circle which is smaller than the diameter of the ball, the outer free ends of the gripping arms being free to flex and bowed to form ball-pocketing fingers, the fingers resiliently engaging the ball and being expanded and spring tensioned thereby, and being disposed on the ball past its maximum diameter, whereupon the resilient gripping arms react and cause the bowed fingers to contract, thus clasping the ball surface at positions beyond its maximum diameter.
